TIE RACK

Sol N. Chaika, Bronx, N. Y.

Application June 20, 1946; Serial No. 678,103

12 Claims.

(CL. 211—100)

1

This invention relates to rack devices for supporting ties and similar articles in close arrangement one with respect to the other. More particularly, the invention deals with a rack of the character described comprising a plurality of supporting rods with means for clamping said rods in grouped snug engagement one with respect to the other in the support for the rod or with articles arranged upon the rod. Still more particularly, the invention deals with a rack having means for pivotally mounting the rod supporting frame or arm to facilitate movement thereof into different positions. The novel features of the invention will be best understood from the following description when taken together with the accompanying drawing in which certain embodiments of the invention are disclosed, and in which, the separate parts are designated by suitable reference characters in each of the views, and in which:

Fig. 1 is a side view of a rack illustrating a use thereof, with part of the construction in section and showing the rack in a lower position in dot-dash lines.

Fig. 2 is a plan view of a rack similar to that shown in Fig. 1, with parts in a different position and with part of the construction broken away and in section.

Fig. 3 is a section on the line 3—3 of Fig. 1.

Fig. 4 is a section on the line 4—4 of Fig. 1 on an enlarged scale; and

Fig. 5 is a sectional view through the bracket and bracket end portion of the rack having the swinging arm of the rack in a partially lower position.

In illustrating one adaptation of my invention, I have shown a rack comprising a bracket part 10 adapted to be secured to a suitable support, part of which is shown at 11 in Figs. 1 and 5, and at 12 I have shown a swinging arm having a pivotal mounting in connection with the bracket, as later described.

The arm 12 is formed from two similar strips of material 13 and 14, each of which is of channel cross sectional form, as seen in Fig. 1 of the drawing, these strips having at the outer end of the arm inwardly turned wall portions 15 and 16 to which is secured an end plate 17 by rivets, as at 18. The plate 17 supports the parts 13 and 14 in spaced relationship to each other, and these parts are further spaced by two sleeves 19 and 20, through which are passed rivet pins 21 and 22 respectively. This construction forms on the arm 12 elongated side passages 23 which extend the full length of the parts 13 and 14 and in which

are slidably mounted a plurality of tie supporting rods 24. Each of the rods 24 are of the same construction, therefore, the brief description of one will apply to all.

Each rod has reduced ball like or rounded ends 25 and central portions of the rods have pairs of circumferential recesses 26 which fit in the passages 23 or in other words, the reduced diameters of the rods formed by the recesses 26 are substantially equal to the width of the elongated slots or passages 23 to provide free sliding action of said rods in the arm 12, whereas the larger diameters of the rods engage the side walls 27 of the part 13, and 28 of the part 14 in retaining the rods against shifting and displacement.

The bracket 10 comprises a U-shaped body defined by side walls 29 joined by a back cross head 30, the latter having upwardly and downwardly extending apertured extensions 31 adapted to receive screws or other fastening devices 32 in attachment of the bracket to the support, as at 11. The side walls 29 are joined by two inner and outer rivet pins 33 and 34, both of which are adapted to fit in the slots 23 in supporting the arm 12 in the raised or extended position shown in full lines in Fig. 1, whereas the pin 34 forms a pivotal support around which the arm swings, with the sleeve 20 resting upon the pin 34 in the manner partially indicated in Fig. 5 of the drawing.

It will also be understood that the outer edges of the side plates 29 of the bracket 10 form stops limiting movement of the rods 24 in one direction, the rods being moved in the direction of the bracket and held in such position by a holding element 35. The element 35 comprises a pair of elongated knobs 36 having circumferential recesses 37 on inner adjacent end portions thereof, the recesses being of sufficient width to provide inward and outward movement of the knobs 36 against the action of a spring 38, the latter serve to hold the knobs in an outwardly extending position. Arranged upon the inner ends of the knobs within the arm 12, or between the walls 27 and 28, is a sleeve 39, and this sleeve is adapted to engage the outermost rod 24, for example, the rod 24 in moving all of the rods in the direction of the bracket 10, with the arm 12 in the position shown in full lines in Fig. 1. By pushing inwardly upon the knobs 36 by two fingers of a hand, the element 35 may be freed to move outwardly on the arm to the sleeve 39, freeing all of the rods for attachment of ties, as at 40 upon the rods, or a predetermined number of rods, it being understood that at least two ties can be

supported on each rod one at each end portion of the rod, or at each side of the arm 12.

In the present disclosure, the size of the ties are somewhat exaggerated. In most instances, the ties are relatively thin and it will be apparent that a larger number of ties may be supported upon the rods of the rack. When all ties have been mounted, the element 35 is moved in the direction of the bracket to bring all of the rods into close engagement with each other clamping the ties in position, thus preventing accidental displacement of the ties. In detaching a tie, the above operation is reversed.

Having fully described my invention, what I claim as new and desire to secure by Letters Patent is:

1. A rack of the class described comprising a U-shaped bracket adapted for attachment to a supporting surface, means slidably and pivotally mounting a frame in connection with said bracket and extending therefrom, said frame comprising a double channel body with the channels arranged opposed to each other in the frame, means spacing said channels to form openings extending longitudinally of opposed side portions of the frame, a plurality of rods mounted in the frame and extending at opposite sides of the frame through the side openings therein, said rods having circumferentially grooved portions engaging said channelled members in retaining the rods against displacement from the frame, and means comprising a resilient clamp slidably engaging the frame for retaining the rods in grouped arrangement one with respect to the other in said frame.

2. A rack of the class described comprising a U-shaped bracket adapted for attachment to a supporting surface, means slidably and pivotally mounting a frame in connection with said bracket and extending therefrom, said frame comprising a double channel body with the channels arranged opposed to each other in the frame, means spacing said channels to form openings extending longitudinally of opposed side portions of the frame, a plurality of rods mounted in the frame and extending at opposite sides of the frame through the side openings therein, said rods having circumferentially grooved portions engaging said channelled members in retaining the rods against displacement from the frame, means comprising a resilient clamp slidably engaging the frame for retaining the rods in grouped arrangement one with respect to the other in said frame, and said first named means comprising spaced pivot and lock pins in the bracket passing through the openings of said frame, the lock pin engaging the frame openings in supporting said frame in outwardly extended position with respect to the bracket.

3. A rack of the class described comprising a U-shaped bracket adapted for attachment to a supporting surface, means slidably and pivotally mounting a frame in connection with said bracket and extending therefrom, said frame comprising a double channel body with the channels arranged opposed to each other in the frame, means spacing said channels to form openings extending longitudinally of opposed side portions of the frame, a plurality of rods mounted in the frame and extending at opposite sides of the frame through the side openings therein, said rods having circumferentially grooved portions engaging said channelled members in retaining the rods against displacement from the frame, means comprising a resilient clamp slidably engaging the

frame for retaining the rods in grouped arrangement one with respect to the other in said frame, said first named means comprising spaced pivot and lock pins in the bracket passing through the openings of said frame, the lock pin engaging the frame openings in supporting said frame in outwardly extended position with respect to the bracket, said frame being adapted to hang in a vertical position with respect to said pivot pin when released from the lock pin, and one of the means spacing the channel members of the frame forming a stop checking outward movement of the frame and forming a support for the frame on said pivot pin.

4. A rack of the class described comprising a U-shaped bracket adapted for attachment to a supporting surface, means slidably and pivotally mounting a frame in connection with said bracket and extending therefrom, said frame comprising a double channel body with the channels arranged opposed to each other in the frame, means spacing said channels to form openings extending longitudinally of opposed side portions of the frame, a plurality of rods mounted in the frame and extending at opposite sides of the frame through the side openings therein, said rods having circumferentially grooved portions engaging said channelled members in retaining the rods against displacement from the frame, means comprising a resilient clamp slidably engaging the frame for retaining the rods in grouped arrangement one with respect to the other in said frame, said first named means comprising spaced pivot and lock pins in the bracket passing through the openings of said frame, the lock pin engaging the frame openings in supporting said frame in outwardly extended position with respect to the bracket, said frame being adapted to hang in a vertical position with respect to said pivot pin when released from the lock pin, one of the means spacing the channel members of the frame forming a stop checking outward movement of the frame and forming a support for the frame on said pivot pin, said resilient clamp comprising a pair of short hollow pins freely keyed to the channel members of the frame, a spring normally urging the pins outwardly, and a sleeve forming a guide for inner ends of the pins within said frame.

5. In racks of the class described, a pair of frame members, each of channel cross sectional form, means coupling said members with the channels arranged in opposed directions to each other and with side walls of said channels in alignment and spaced apart to form elongated openings longitudinally of side walls of the frame, said means forming end stops at end portions of the frame, and a plurality of article supporting members mounted in said frame and having grooves engaging the side walls of the channel members of the frame in retaining said article supporting members against displacement from the frame while permitting sliding movement of the members in the frame.

6. In racks of the class described, a pair of frame members, each of channel cross sectional form, means coupling said members with the channels arranged in opposed directions to each other and with side walls of said channels in alignment and spaced apart to form elongated openings longitudinally of side walls of the frame, said means forming end stops at end portions of the frame, a plurality of article supporting members mounted in said frame and having grooves engaging the side walls of the channel members

of the frame in retaining said article supporting members against displacement from the frame while permitting sliding movement of the members in the frame, and means including a resilient clamp for retaining said article supporting members in predetermined grouped position in the frame.

7. In racks of the class described, a pair of frame members, each of channel cross sectional form, means coupling said members with the channels arranged in opposed directions to each other and with side walls of said channels in alinement and spaced apart to form elongated openings longitudinally of side walls of the frame, said means forming end stops at end portions of the frame, a plurality of article supporting members mounted in said frame and having grooves engaging the side walls of the channel members of the frame in retaining said article supporting members against displacement from the frame while permitting sliding movement of the members in the frame, and means comprising a bracket for pivotally and slidably supporting one end of the frame.

8. In racks of the class described, a pair of frame members, each of channel cross sectional form, means coupling said members with the channels arranged in opposed directions to each other and with side walls of said channels in alinement and spaced apart to form elongated openings longitudinally of side walls of the frame, said means forming end stops at end portions of the frame, a plurality of article supporting members mounted in said frame and having grooves engaging the side walls of the channel members of the frame in retaining said article supporting members against displacement from the frame while permitting sliding movement of the members in the frame, means comprising a bracket for pivotally and slidably supporting one end of the frame, and means forming a closure for the other end of the frame.

9. In racks comprising a frame having longitudinal slots and a plurality of supporting members slidably mounted in the slots in the frame, means for retaining said members in predetermined grouped position in the frame, said means comprising a pair of clamp elements having inner opposed socket portions, means keying said elements for movement longitudinally of the frame, a coil spring mounted in the sockets of said elements normally supporting the same in clamped engagement with the frame while permitting free movement of the elements in the frame upon movement of the elements toward each other against the tension of said spring.

10. In racks comprising a frame having longitudinal slots and a plurality of supporting members slidably mounted in the slots in the frame, means for retaining said members in predetermined grouped position in the frame, said means comprising a pair of clamp elements having inner opposed socket portions, means keying said elements for movement longitudinally of the frame, a coil spring mounted in the sockets of said elements normally supporting the same in clamped engagement with the frame while permitting free movement of the elements in the frame upon movement of the elements toward each other against the tension of said spring, and means comprising a sleeve forming a cover and guide for inner adjacent ends of said elements.

11. In tie racks of the class described, an elongated rigid arm having side passages, a bracket supporting one end of the arm, a plurality of article supporting rods, said rods having grooves for slidable connection to said arm and movable longitudinally of said arm in said passages, a retaining element movable longitudinally of said arm, and said element having means engaging the arm to retain said rods in close proximity to each other in the arm.

12. In tie racks of the class described, an elongated rigid arm having side passages, a bracket supporting one end of the arm, a plurality of article supporting rods, said rods having grooves for slidable connection to said arm and movable longitudinally of said arm in said passages, a retaining element movable longitudinally of said arm, said element having means engaging the arm to retain said rods in close proximity to each other in the arm, and means forming stops at each end of the arm for checking movement of the rods and element therein.
